US00D817301S

(12) **United States Design Patent** (10) **Patent No.:** **US D817,301 S**
(45) **Date of Patent:** ** *May 8, 2018

(54) **HEADPHONES**

(71) Applicant: **Apple Inc.**, Cupertino, CA (US)

(72) Inventors: **Shota Aoyagi**, San Francisco, CA (US);
Robert Boyd, Los Angeles, CA (US);
Robert Brunner, San Francisco, CA (US);
Monica Fernandez, Los Angeles, CA (US);
Christopher Kuh, San Francisco, CA (US); **Christopher J. Stringer**, Woodside, CA (US)

(73) Assignee: **Apple Inc.**, Cupertino, CA (US)

(*) Notice: This patent is subject to a terminal disclaimer.

(**) Term: **15 Years**

(21) Appl. No.: **29/575,696**

(22) Filed: **Aug. 26, 2016**

(51) LOC (11) Cl. **14-01**

(52) U.S. Cl.

USPC **D14/205**

(57) **CLAIM**

The ornamental design for headphones, as shown and described.

DESCRIPTION

FIG. 1 is a front perspective view of headphones showing the claimed design;

FIG. 2 is a front view thereof;

FIG. 3 is a rear view thereof;

FIG. 4 is a left side view thereof;

FIG. 5 is a right side view thereof;

FIG. 6 is a bottom view thereof; and,

FIG. 7 is a top view thereof.

The broken lines in the figures show portions of the headphones that form no part of the claimed design.
